UNITED STATES PATENT OFFICE

HARRY W. KRAG, OF ST. LOUIS, MISSOURI, ASSIGNOR TO AMERICAN SHOE MACHINERY AND TOOL COMPANY, OF ST. LOUIS, MISSOURI, A CORPORATION OF MISSOURI

CUTTING MACHINE

Application filed January 3, 1927. Serial No. 158,573.

This invention relates to splitting machines of the fixed-knife, gear-driven, roller-feed type for splitting and levelling leather. The invention has for its principal objects to provide ample gear reduction, to provide for the proper housing of the reducing gears, to provide proper support for and intermeshing of the driving gears and to obtain other advantages hereinafter appearing.

The invention consists principally in the parts and in the combinations and arrangements of parts hereinafter described and claimed.

In the accompanying drawing, which forms part of this specification and wherein like symbols refer to like parts wherever they occur.

Fig. 1 is a front elevation of a leather splitting machine embodying my invention, parts being shown broken away to more clearly illustrate said invention;

Fig. 2 is an end view of said machine;

Fig. 3 is a fragmentary plan view showing the gear housing and the portions of the machine located adjacent thereto; and

Fig. 4 is a vertical section taken on the line 4—4 looking in the direction of the gear box.

Referring to the accompanying drawing, my invention is shown in connection with a leather splitting machine of the fixed-knife, gear-driven, roller-feed type. The frame of said machine comprises spaced uprights or standards 4 connected at the top by a cross-head 5 and at the bottom by a base portion 6 adapted to be bolted or otherwise rigidly secured to a table or work bench (not shown). Located below the cross-head 5 of the frame, between the spaced uprights 4 thereof, are horizontally journaled cooperating upper and lower feed rolls 7 and 8, respectively, adapted to feed the work against the cutting edge of a knife 9 adjustably supported on a supporting bracket 10 bolted to the front faces of said uprights.

The knife supporting bracket 10 is disposed at a height adapted to place the cutting edge of the knife 9 in a position to receive the work which is fed thereto by the pair of cooperating feed rolls 7 and 8. In

front of the lower feed roll, near the top thereof, is a work supporting bracket or guide in the form of a shelf 10^a which extends horizontally from upright to upright and is integral therewith.

The upper feed roll 7 is fixed to a horizontal shaft 11 journaled at its opposite ends in bearing blocks 12 slidably mounted in vertical slideways 13 provided therefor in the spaced uprights 4; and likewise, the lower feed roll 8, whose peripheral surface is corrugated, is fixed to a horizontal shaft 14 whose ends are rotatably supported in bearing blocks 15 that are also slidably mounted in the vertical slideways 13 of said uprights.

Each of the bearing blocks 15 for the lowermost feed roll shaft 14 is supported on the upper end of a vertical pin 16, which is slideable in a vertical bore provided therefor in a cross member 17 at the lower end of each vertical slideway 13. The upper end of each pin 16 is threaded into a bearing block 15, and its lower end is rotatably supported at its lower end in a depression in a metal disk 18, which is seated in a circular depression formed in a pressed metal disk 19 supported on the upper end of a coil spring 20. Each coil spring 20 is supported at its lower end on a metal disk 21 which, in turn, is supported on the upper end of a vertical adjusting screw 22 threaded through a horizontal lug 23 on the frame. Each adjusting screw 22 has a tapered upper end portion which has a bearing in a central circular opening provided therefor in the disk 21 supported thereon.

By this arrangement, the lower feed roll 8 is adapted to yield slightly under pressure of the work, but also holds the work against the cooperating surface of the upper feed roll 7. As shown in the drawing, upward movement of the lower feed roll 8 is limited by locking nuts 24, which are threaded on the vertically slideable supporting pins 16 for the blocks and abut against the under sides of the cross members 17 at the lower ends of the vertical slideways 13.

The upper feed roll 7 is yieldably supported by means of coil springs 25 interposed between the upper and lower bearing blocks 12 and 15, respectively. The upper feed roll 7 is supported on the upper end of a vertical adjusting screw 26 threaded through a horizontal lug 27 on the frame. Each adjusting screw 26 has a tapered upper end portion which has a bearing in a central circular opening provided therefor in the disk 21 supported thereon. The upper feed roll 7 is yieldably supported by means of coil springs 25 interposed between the upper and lower bearing blocks 12 and 15, respectively. The upper feed roll 7 is supported on the upper end of a vertical adjusting screw 26 threaded through a horizontal lug 27 on the frame. Each adjusting screw 26 has a tapered upper end portion which has a bearing in a central circular opening provided therefor in the disk 21 supported thereon.

is adjusted towards and away from the lower feed roll 8 to vary the thickness of the split leather by means of a cross bar 26 which is located beneath the cross-head 5 of the frame and has beveled end portions 27 which cooperate with the upper surfaces of the bearing blocks 12 for the upper feed roll 7 and act after the manner of wedges for forcing said blocks downwardly against the pressure of the supporting springs 25 when the slide bar is moved or shifted endwise in the proper direction to secure the desired thickness of split leather. The wedge bar 26 is shifted endwise by means of an adjusting lever 28 which is pivoted to the cross-head 5 of the frame for a vertical swinging movement by means of a horizontal pivot screw 29. The lower arm of the adjusting lever 28 has a bifurcated end portion which straddles a pin 30, which projects horizontally from the slide bar 26; and the upper arm of said adjusting lever is provided with an arcuate slot 31 adapted to accommodate a horizontal pin 32 fixed to an upstanding ear 33 on the cross member 5 of the frame. The pin 32 extends through the upwardly extending portion of a gage plate 34, which is secured to the frame by the pivot screw 29, and is threaded to receive a thumb screw 35, whereby the adjusting lever 28 may be locked in the desired adjusted position. The lower edge of the gage plate 34 is graduated to indicate split leather in irons; and the outer end of the pin 30 carried by the wedge bar 26 is of triangular section and has one corner which cooperates with the graduations on the gage plate and serves as an indicator. As shown in the drawing, the cross-head 5 of the frame is provided with stop screws 36, which prevent upward movement of the wedge bar and constitute means for adjusting the top roll so that it is parallel to the knife.

The upper and lower feed rolls are both positively driven by gearing located in a gear housing 37 located at one end of the frame. The side walls of said gear housing are provided with axially aligned holes adapted to receive the adjacent end of the vertically movable lower feed roll shaft 14, whereby said housing is supported on and moves with said feed roll shaft. As shown in the drawing, the inner side wall of the gear box 37 is provided with an opening 37a which receives the adjacent portions of the upper feed roll shaft and the bearing block therefor and is made large enough to permit vertical adjustment of said bearing block and feed roll shaft and to permit vertical sliding movement of the gear box with the lower feed roll shaft, which supports said gear box. Rotation of the gear housing on the lowermost feed roll shaft is prevented by means of a horizontal tongue or projection 38 on the top of the housing which projects between the opposing faces of the vertical slideway in the upright adjacent

thereto. The gearing for driving both feed rolls comprises a pinion 39 disposed within the housing and fixed to a horizontal shaft 40 journaled in bearings 41 provided therefor in the opposing side walls of said housing. The pinion shaft 40 projects beyond the outer side wall of the gear housing and is provided with a suitable handle or crank 42 for turning it. Fixed to the lower feed roll shaft, between the opposing side walls of the housing supported thereon, are two gears 43 and 44 of different diameters. The outer of these two gears is the larger one 43 and is of proper size to mesh with the pinion 39 provided therefor in the gear housing. The second or inner gear 44 is a smaller gear in position to intermesh with a gear 45 which is fixed to the adjacent end of the upper feed roll shaft 11 within the gear housing and is of the same diameter as the inner gear 44 on the lower feed roll shaft 14.

In the operation of the machine the bottom feed roll is adjusted by means of the adjusting screws 22 to bring the top of said roll parallel to and substantially at the level of the cutting edge of the knife; and the machine is then set to remove the desired thickness of leather from the bottom of the stock by means of the gage lever 28. When thus adjusted, the distance between the top roll and the cutting edge of the knife corresponds substantially to the thickness of the leather that is to be removed from the bottom of the stock. The stock that is to be split or leveled is then placed on the shelf 10 at the rear of the machine with the grain side uppermost and moved into engagement with the cooperating feed rolls which are then rotated by turning the crank 42, whereupon the stock is drawn between the rolls and forced against the cutting edge of the knife blade 9. As the strip passes between the rotating feed rolls, the lower roll is forced downwardly against the pressure of its supporting springs 20, a distance corresponding approximately to the thickness of the leather that is to be removed from the bottom of the stock; and, if the strip has a tapering cross-section, the bottom roll will accommodate itself automatically to the under surface of the strip by tilting on said springs.

As shown in the drawing, the depth of the teeth of the intermeshing gears 45 and 44 on the upper and lower feed roll shafts 11 and 14, respectively, is such that the two gears remain in mesh when the lower gear moves downwardly with the lower feed roll. It is also noted that the gear housing or guard 37 is supported on and moves with the lower feed roll shaft and that the drive pinion 39, which meshes with the large reducing gear 43 fixed to said lower feed roll shaft, is journaled on and moves with said housing, said shaft and said reducing gear. By this arrangement of drive gearing, the intermeshing pinion 39 and

reducing gear 43 move with the lower feed roll 8; and the centers of the two meshing gears are kept in fixed relation to each other and are thus prevented from separating when working under load.

5 Obviously, numerous changes may be made without departing from the invention and I do not wish to be limited to the precise construction shown.

10 What I claim is:

1. A skiving machine comprising a frame, a skiving knife, a pair of cooperating upper and lower feed rolls rotatably supported in said frame for feeding the work against said knife, said lower feed roll being arranged for vertical sliding movement towards and away from said upper feed roll, gearing for driving said upper and lower feed rolls, and a housing for said gearing mounted on and movable with said vertically movable lower feed roll, said gearing comprising a gear rotatably supported in said gear housing and meshing with a gear on said lower feed roll, and intermeshing gears on said pair of cooperating upper and lower feed rolls, said housing comprising inner and outer side walls having openings therein adapted to fit the lower feed roll, the inner wall of said housing having an opening therein adapted to receive the upper feed roll shaft and large enough to permit movement of the housing relative thereto.

2. A skiving machine comprising a frame, a skiving knife, a pair of cooperating upper and lower horizontal feed rolls rotatably supported in said frame for feeding the work against said knife, said lower feed roll being mounted in said frame for vertical sliding movement towards and away from said upper feed roll, gearing for driving said upper and lower feed rolls, and a housing for said gearing mounted on said vertically movable lower feed roll, said gearing comprising a drive pinion rotatably supported in said gear housing, a reducing gear on said lower feed roll and meshing with said pinion, and intermeshing gears on said pair of cooperating upper and lower feed rolls, all of said gears being located within said housing.

35 40 45 Signed at St. Louis, Missouri, this 29 day
50 of Dec., 1926.
